THERMOELECTRIC GENERATOR AND
CASING THEREFOR

Charles E. Bodey, St. Paul, Minn., assignor
to Minneapolis-Honeywell Regulator Company,
Minneapolis, Minn., a corporation of Delaware

Application November 24, 1947, Serial No. 787,665

6 Claims. (Cl. 136—4)

1

This invention relates to improvements in thermoelectric generators of the type comprising a thermocouple unit and an associated burner for heating said unit. More particularly, the invention is concerned with the unit which transforms heat into electrical energy, namely, the thermocouple unit of the generator.

Thermoelectric generators of the above mentioned type are well known in the art. The numerous designs differ widely as to the burner construction and the construction of the associated thermocouple or combination of thermocouples, commonly known as thermopiles, and as to their relative positions.

While most of the prior art generators of the above mentioned type are satisfactory for a good many of the applications for which they are designed, none of them is wholly satisfactory for use in an installation requiring that the thermoelectric generator be small in size, must operate with relatively small heat generation, and must produce a comparatively high and uniform electrical output throughout its operating life. This deficiency on the part of the prior art devices is due to the fact that the cases on the thermocouples gradually oxidize inside and out and, particularly, at the hot junction ends thereof when said ends are continuously heated. The oxide, being a poor heat conductor, causes a decrease in electrical output and thus faulty operation of the system controlled by said electrical output. This makes it necessary for the systems in which the prior art devices are used to be checked and adjusted from time to time to keep the systems in proper working order.

An object of this invention is to provide a small and relatively inexpensive thermopile type of an electric generator that substantially maintains its electrical output throughout its operating life.

Another object of the invention is to provide a thermopile that is highly efficient.

A further object of the invention is to provide a thermopile case or shell which may be formed substantially from sheet material.

Another object of the invention is to provide a thermopile case or shell that has dark oxidized inner and outer surfaces.

Still another object of the invention is to provide a thermopile having mounting means thereon which permits its adjustment toward and away from an associated burner for heating it.

Still further objects of the invention will become apparent upon reading the following detailed description of the invention in conjunction with the accompanying drawings wherein:

2

Figure 1 is an elevational view of the thermoelectric generator with parts thereof broken away;

Figure 2 is a cross-sectional view taken on a plane extending longitudinally through the thermopile;

Figure 3 is a cross-sectional view taken on the line 3—3 of Figure 2;

Figure 4 is a bottom view of the thermopile with portions thereof broken away; and

Figure 5 is a plan view of the main body portion of the thermopile case as it appears before being bent into the shape of an open-sided casing.

Referring now to Figure 1 of the drawing, the 15 thermoelectric generator comprises a thermopile, generally designated by the numeral 10, a pilot burner 11, and a bolt 12 passing through bracket members 13 and 14 on the thermopile and pilot burner, respectively, for adjustably securing them 20 together.

The details of the pilot burner 11 form no part 25 of this invention. It is of the well known type wherein orifices are provided for directing one flame against the upper "hot junction" end of the thermopile and another flame over an associated main burner (not shown) to ignite it. A runner or carrier flame, for reigniting either one of said orifices from the other orifice, is provided for by means of a slot in the side wall of the 30 pilot burner extending from one orifice to the other.

The bracket 14, which is staked or otherwise fastened around the pilot burner body, is adapted to be secured to the wall of a furnace 35 (not shown) or a main burner (not shown) by any suitable fastening means. The right hand end of the bracket 14 is slotted so as to receive the thermopile 10 and has spaced upper and lower walls 15 and 16, respectively, which are adapted to snugly receive therebetween a laterally projecting portion 17 of the bracket 13. The above mentioned bolt 12 passes freely through an opening in the bottom wall 16 of the bracket 14, through spaced slots in the laterally projecting 40 portion 17 of the bracket 13 and is screw-threaded into an opening in the top wall 15. Tightening of the bolt 12 draws the bottom wall 16 and upper wall 15 tightly against the portion 17 to frictionally hold the thermopile 10 in its adjusted 45 position relative to the pilot burner 11.

Referring now to Figures 2, 3, 4 and 5, the thermopile 10, which forms the major portion of this invention, comprises a casing 18 which is formed out of sheet steel, preferably stainless 50 steel containing some nickel. The casing is first

cut into the shape shown in Figure 5, then stamped to form the indentations 19, then bent sharply along the dotted lines to form unjoined side walls 20 and 21, having ears 20a and 21a, and bottom wall 22. The top wall 23 is also bent but on a sufficiently large radius so as to cause its side edges to bear against the inner surfaces of walls 20 and 21 adjacent their upper edges. The bracket 13 is then spot-welded or connected in any other suitable manner to the front wall 24 of casing 18.

A cover 25, similarly formed from the same kind of sheet material, has an extruded portion 26 surrounded by a ferrule 27 which fits snugly around a lead wire cable 28 passing therethrough. Cover 25 also has a bottom flange 29, side flanges 30 and 31 and projection 32 which bear against the outer surfaces of the walls 22, 20, 21 and 23, respectively, and hold said walls in their folded positions. Slots 25a in the cover receive the ears 20a and 21a which are bent over on the outer surface of the cover to hold it on the casing 18.

The above mentioned casing and cover have darkened or blackened inner and outer surfaces, as illustrated at 33 and 34, respectively, which are so made by dipping the casing and cover in a very hot bath of sodium dichromate for from five to ten minutes. This treatment oxidizes the surface iron, chromium, and nickel in the sheet material to form substantially black inner and outer surfaces thereon. This blackening or oxidizing of the surfaces of the casing and its cover enables the complete case to perform many useful and improved functions to be described herein-after.

A simple thermopile comprising series-connected, alternately-spaced, thermoelectrically dissimilar metals 35 and 36 having oxidized insulation surfaces, as illustrated at 36a, is of the same general shape as the above mentioned casing, but has smaller overall dimensions. The hot and cold junctions are preferably made by spot-welding. The end elements 35 and 36 have downwardly and inwardly extending projections 37 and 38, respectively, thereon which are wrapped around and soldered or otherwise suitably secured to the ends of lead wires 39 and 40, respectively. These projections and ends of the lead wires are held spaced apart by means of an insulation plate 41. The thermopile elements 35 and 36 are held spaced from the casing 18 and cover 25 by means of strips of mica or other insulating material 42 and 43 and indentations 19 as well as by heat conducting, electrically insulating, ceramic cement 44 packed into and filling the case.

In assembling the above mentioned elements of the thermopile, the casing 18 is held with its longitudinal axis in a horizontal position, with the open side up. A thin layer of the ceramic cement 44 is spread over the inner surface of the wall 24. The sheet of mica 42 is then positioned over this cement to insure spacing of the longitudinal edges of the thermopile elements from said wall 24. This sheet of mica extends from the wall 22 to approximately three-fourths of the length of the wall 24. The thermopile elements are then inserted so as to rest on this sheet of mica. The second sheet of mica 43 is then positioned over the opposite edges of the thermopile elements and is of such length as to extend substantially the full length of said edges. More of the same ceramic cement is then forced all around the thermopile elements with

5 a surplus amount piled up thereon so as to force some of the cement up into the extruded portion 26 of the cover member 25 in the next step. This next step consists in sliding the cover 25 down over the cable 28 into its position on the open side of the casing with the ears 20a and 21a extending through the slots 25a. The ears 20a and 21a are then bent inwardly over the outer surface of the cover 25 to lock it in position. 10 The final processing step consists of baking the assembled unit to harden the cement.

Operation

With the thermopile mounted on the pilot burner as shown in Figure 1, with the pilot burner connected to a suitable source of fuel and the leads 39 and 40 of the thermopile connected to a suitable load such as the above mentioned system, a flame issuing from one of the orifices in the pilot burner and impinging on the upper portion of the thermopile causes the generation of electricity by the thermopile and energization of the load. Depending upon the nature of the fuel being burned, whether it is natural gas, or manufactured gas or mixtures of both, the flame will have certain characteristics. It has been found that due to these differing characteristics, it is highly desirable, if not absolutely necessary, to be able to adjust the position of the thermopile with respect to the pilot burner so as to have the flame impinge properly on the thermopile. It can be readily seen that the mounting bracket for applicant's thermopile permits easy and quick adjustment thereof to assure optimum efficiency of operation of the generator by merely loosening screw 12, sliding the thermopile to the proper position, and then tightening the screw.

Furthermore, the blackening on the outer surface of the hot junction end of the thermopile increases the radiant heat absorption properties thereof which partly offsets the loss in efficiency or output due to reduction of heat transfer by conduction thru the oxidized or blackened surfaces of the case to the ceramic material and the hot junction ends of the thermopile elements.

Likewise, the blackened outer surface at the cold junction end of the thermopile casing, due to its better heat radiating properties, more than offsets the loss of efficiency due to the drop in heat transfer by conduction from the cold junction end of the thermopile element through the blackened inner and outer surfaces of the cold junction end of the shell or case.

It is thus seen that the provision of highly oxidized inner and outer wall surfaces of the thermopile shell performs multiple functions when applied to a thermoelectric generator of the type described. First, due to the fact that the inner and outer surfaces are highly oxidized in the manufacture of the device, there will be no change in the condition of the surfaces throughout the thermopile's operating life. Secondly, the blackened outer surface provides more efficient radiant heat absorption from the flame and emission of heat from the cold junction end of the case, enabling a smaller quantity of gas to be burned or the use of a thermopile of small size. Thirdly, the blackened outer surface at the cold junction end of the thermopile provides more efficient heat dissipation than an unblackened surface so as to maintain the cold junction end at a lower temperature and thus produce a higher output from the thermopile. This is due to the fact that a greater percentage of the heat dissipated there is due to radiation.

Fourthly, the above mentioned blackened surfaces enables the thermopile to be of small size for use in cramped spaces, due to the fact that more stable heating and better cooling of the hot and cold junctions, respectively, is obtained without having to use prior art cooling fins on the case.

It is also to be noted that by having the hot junction ends of the thermopile elements welded together near their ends and the side edges thereof adjacent the front surface 24 of the casing, and all of the edges of said elements facing said front wall, the burner flame is spread over this flat surface front wall so as to uniformly heat these edges very close to the hot junctions.

As modifications of this invention may be made without departing from the spirit thereof, it is to be understood that the scope of the invention is to be determined solely by the appended claims.

I claim as my invention:

1. In a thermoelectric generator, a thermoelectric unit, a protective case for said thermoelectric unit comprising a main body portion of oxidized sheet material in the form of an open-sided casing, ears on said casing extending beyond said open side, and a cover member having openings therein through which said ears extend and flanges thereon engaging side walls of said body portion, said ears being bent transversely for holding the container's side walls together and said cover member on said container.

2. In a thermoelectric generator, a thermoelectric unit, a steel case having oxidized inner and outer surfaces for enclosing said thermoelectric unit, and heat-conducting electricity insulating material between said unit and said case.

3. In a thermoelectric generator, a thermoelectric unit formed of dissimilar metal elements, the surfaces of which are oxidized, a protective case for said thermoelectric unit, said case being composed at least partly of steel and the inner and outer surfaces thereof being highly oxidized.

4. A thermoelectric generator comprising a metallic case having one end thereof so con-

structed as to operatively withstand the impingement of a flame thereon, said end having oxidized inner and outer surfaces at the point of flame impingement, and a thermocouple within said case having a hot junction portion positioned within said end of said case.

5. In a thermoelectric generator, a thermoelectric unit having a hot junction and a cold junction, a thin wall metallic case housing at least said hot junction and arranged to be heated by a flame adjacent said hot junction, said case having highly pre-oxidized inner and outer surfaces.

6. In a thermoelectric generator, a thin wall metallic protective case for a thermoelectric unit wherein the inner and outer surfaces at least at the area of the case to be heated are highly oxidized.
